Cooper, Kerr & Dunham

UNITED STATES PATENT OFFICE

GEORGE BAUMGARD, OF CARLSTADT, NEW JERSEY, ASSIGNOR TO EAGLE PENCIL COMPANY, OF NEW YORK, N. Y., A CORPORATION OF DELAWARE

PENCIL DISPLAY CARTON

Application filed November 30, 1929. Serial No. 410,683.

This invention relates generally to display cartons and has particular reference to devices of that general nature which are adapted for use in displaying pencils.

An object of the invention is to provide a carton or holder which may readily be changed from a covered container to an open one supported by an easel in such a way that the pencils may readily be seen.

Incidental objects are to provide a construction which can be manufactured at a low cost but which is, nevertheless, strong and durable in use.

The specific embodiment disclosed herein is adapted to serve both as a display carton for sales purposes and as a convenient device for holding a set of pencils exposed in such a way that the user may quickly select any one desired. This is particularly desirable for use in connection with a set of colored pencils or the like. While the device disclosed is referred to herein as a display carton, that term is employed mainly for convenience and is not intended in any way as a limitation to any particular use.

The terms "upper", "lower", "front", "rear", and "back", are used in describing the construction and in the claims, but these terms are also used for convenience and not for the purpose of imposing any limitations.

With the foregoing and other objects and advantages in view, the invention is herein-after explained as embodied in the construction shown in the accompanying drawing.

The novel features of that invention in its broader aspects are pointed out in appended claims.

In said drawing:

Figure 1 shows a perspective view of one of the devices as it appears when closed to form a container for a set of pencils.

Fig. 2 is a view, on the line indicated by the arrow 2 in Fig. 1, of the upper rear portion of the container with a part of the cover broken away to expose to view one of the fastening devices.

Fig. 3 is a perspective showing the device arranged to give an easel support for the pencil box or container.

Fig. 4 is a rear view, substantially on the

line indicated by the arrow 4 in Fig. 3, and shows the manner in which the flexible cover is attached to form an easel to support the container.

The device shown in the drawing has a back 10, two sides 11, and a short piece 12 attached between the sides 11 and forming what might be termed a short front for a box. The box may be of any convenient width, but is shown as it would appear when constructed to hold a set of seven pencils.

Attached to the short front 12 is a member 13, formed around the lower part of the box, and having a portion 14 which is preferably secured to the rear of the box. The member 13 is so constructed as to form a hinge or flexible portion 15 and is preferably made somewhat flexible or hinged at 16 and 17. The flexible portions 16 and 17 form corners which, when the box is closed, fit over the corners at the upper end of the box.

The member 13 also comprises a portion 18 terminating in a tab 19 which may be flexible or which has a flexible connection 20 with the portion 18.

The tab 19 carries one member 22 of a well known form of snap fastener. A stud 23 on the lower front of the box, or on the portion attached thereto of the member 13, cooperates with the fastening member 22 to hold the member 13 when it is fitted over the box to form a closure therefor. When the parts are in the relations just described the device will appear as illustrated in Fig. 1.

The upper rear portion of the box also carries a stud 24 to cooperate with the fastening member 22 on the tab 19 when the box is opened up and the various parts of member 13 adjusted to form an easel support for the box. In setting up the box in this way the various sections of the member 13 are adjusted to the position shown in Fig. 3 and the snap fastening member 22 engaged with the stud 24. This forms a comparatively rigid and entirely satisfactory support for holding a set of pencils indicated generally at 25 in displayed position for sale or in a convenient way for selection by a user.

The member 13 may, of course, be so reorganized as to do away with the portion ex-

tending around the lower part of the box and simply made in such a way as to provide a portion corresponding generally to the portion 14 to be attached to the rear of the box. This modification would, of course, involve attaching the stud 23 directly to the front member 12. The member 13 is also jointed at 15, 16, 17 and 20 but it is obvious that the entire member may be made of flexible material which will still have enough stiffness to support the pencil container in substantially the position shown in Fig. 3.

In addition to the modifications specifically referred to, it is apparent that other changes in the construction and relative arrangement of the parts may also be made and still embody the invention. It is, therefore, not the desire to be limited in any respect except as such limitations may appear in the claims which follow.

20 What is claimed is:

1. In a device of the character described, a rectangular receptacle for pencils open at one end, a jointed member hinged on the back of the receptacle which may be fastened in position to serve as a closure for one end and the face of the receptacle and fastened to the back of the container to serve as a supporting easel for said container, and devices on the 25 front and back of the container for fastening the jointed member in either position.
2. A combined pencil container and display holder comprising a rectangular receptacle for the pencils, a jointed member hinged 30 on the back of the receptacle, below the middle of said back, and adjustable to serve either as a closure for the container or as a supporting easel for the container, a snap fastening member attached near the free end 35 of the jointed member, and snap members on the lower front and upper back of the container constructed to cooperate with the snap member on the jointed member.
3. A combined pencil container and display holder comprising a box open at one end and for the larger part of its front, a member secured to the lower front, extending 40 around the bottom and along the back of the box, a member hinged to the upper edge of the first member at the back of the box, and constructed to extend over the top and down 45 the front of the box, a flexible tab on the free end of the second member and carrying a fastening member, and snap fasteners secured 50 to the first member on the front of the box and on the upper rear of the box constructed 55 to cooperate with the fastening member on the aforesaid tab.
4. In a device of the character described, a 60 receptacle for pencils composed of an end portion; two sides and a back substantially the length of the pencils and a front substantially shorter than the length of the pencils; in combination with a member hinged to the 65 exterior of the back and composed of sections

flexibly connected together and adapted to be drawn over the face of the receptacle and fastened to the aforesaid front whereby to effect a closure of the receptacle; and means on the upper back cooperating with means on the 70 end of said member to hold the member in position to serve as a supporting easel for the receptacle.

In testimony whereof I hereto affix my signature.

GEORGE BAUMGARD.
